UNITED STATES PATENT OFFICE

OSWALD H. HANSEN, OF MILWAUKEE, WISCONSIN, ASSIGNEE TO HANSEN CANNING MACHINERY CORPORATION, OF PORT WASHINGTON, WISCONSIN

CAN FEEDING MECHANISM

Original application filed September 22, 1922, Serial No. 589,888. Patent No. 1,677,443, dated July 17, 1928.

Divided and this application filed September 25, 1926. Serial No. 137,797.

This invention relates in general to improvements in the art of transporting or feeding similar objects in succession, and relates more specifically to improvements in the construction and operation of mechanisms for automatically and positively delivering receptacles such as cylindrical cans in succession downwardly in accurately spaced relation to each other.

10. An object of the invention is to provide a simple and efficient can feed for delivering tin cans or similar objects in a substantially vertical direction.

Some of the more important specific objects of the invention are as follows:—

To provide improved feeding mechanism which is especially adapted to positively transport cylindrical objects in succession in a downward direction while the axes of the 20 objects are horizontally disposed.

To provide a positive feed for relatively frail objects such as tin cans, which is operated by impositively acting propelling mechanism in order to prevent distortion or 25 damage to the objects.

To provide improved can feeding mechanism for delivering successive cans downwardly in accurately spaced relation to each other.

30. To provide other improvements in the details of construction and operation of can feed mechanisms, whereby the cost of manufacture is reduced to a minimum and the efficiency is enhanced to a maximum.

35. The present application is a division of the application upon which Patent 1,677,443, was granted July 17, 1928, which application covers the novel features of can washer mechanism illustrated but not specifically claimed herein.

A clear conception of an embodiment of the present invention and of the operation of feed mechanisms constructed in accordance therewith, may be had by referring to the 45 drawings accompanying and forming a part of this specification in which like reference characters designate the same or similar parts in the various views.

Fig. 1 is an elevation of an improved vertical can feed showing the same applied to

a can washing machine having the front cover thereof removed.

Fig. 2 is a vertical section through the improved vertical can feeding mechanism and the initial washing chamber of the can washer.

Fig. 3 is a vertical section through the final washing chamber of the improved can washing machine.

Fig. 4 is a top view of the driving mechanism constituting a part of the improved can feed.

The can washer to which the improved can feed has been applied herein by way of illustration, comprises in general a main casing 2 forming a pair of communicating substantially circular chambers; a stationary tubular fluid admission header 3 projecting centrally into each of the chambers; a fluid distributing spider 5 rotatably supported 60 upon each of the headers 3; a can transporting rotor 6 rotatably associated with each of the spiders 5; can supply mechanism associated with the top of the initial washing chamber; a can discharge rotor 8 associated 65 with the final cleansing chamber; suitable mechanism for driving the various movable elements; hot water and steam supply means communicating with the initial and final cleansing chambers respectively; a pivotally supported cover 7 for enabling convenient 70 access to all portions of the interior of the casing 2; and supporting members 24 for suspending the washer from the interior of a factory.

80. Located above the initial washing chamber and adjustably associated with the casing 2, is a can supply chute 12 which is adapted to deliver the successive cans 9 by gravity, in proximity to the vertical can feed mechanism or drum 14. The can feed drum 14 is of enlarging diameter approaching the washer, and has a helical projection 85 15 adapted to engage the successive cans 9 and to gently deposit them in accurately timed relation, into the spaces between the successive advancing can hooks of the first transporting rotor 6. In order to insure proper engagement of the cans 9 with the helical projection 15, the wall of the casing 90 100

2 directly opposite and above the inlet feed mechanism, is provided with guiding projections 43 which are directed downwardly and toward the rotor 15. These projections 43 function to gently push the successive 5 gravitating cans 9 toward the rotor 14 without distorting the cans.

The cleansing chambers are provided with peripheral can guiding rails 44 which are 10 adapted to conduct the successive cans along a definite S shaped course during cleansing thereof. The can transporting rotor 6 and the hot water distributing spider 5 of the initial washing chamber, are simultaneously 15 rotatable in an anti-clockwise direction as viewed in Fig. 1, the can hooks of the initial rotor being formed to receive the cans 9 in succession from the feed drum 14 and to deliver the preliminarily washed cans against 20 an adjustable guide 17 which directs the cans upwardly into the final cleansing chamber. The outer extremities of the arms of the water distributing spider 5 are provided with laterally directed hot water discharge nozzles 25 18 which are formed to deliver the water in the form of films against the side walls and into the corners of the cans while being transported by the initial rotor 6. The water distributing spider 5 and the adjacent rotor 30 6, are drivingly connected by parallel pins 11. The rotor 6 is freely endwise removable from the water distributing spider 5 upon removal of the cap screw and washer, and the spider 5 is likewise endwise removable 35 from the stationary header 3.

The can transporting rotor 6 and the steam distributing spider 5 of the final cleansing chamber, are rotatable in a clockwise direction as viewed in Fig. 1, the can 40 hooks of this rotor being adapted to receive the cans 9 in succession from the rotor 6 of the initial washing chamber, and to deliver the finally cleansed cans against the can hooks of the final discharge rotor 8 which 45 directs the successive cans along an adjustable discharge guide 20 and downwardly through a final discharge passage located below the washer. The outer extremities of the arms of the steam distributing spider 5 50 are provided with laterally directed steam nozzles 19, these nozzles being formed to deliver the steam in the form of films against the side walls and into the corners of the cans while they are being transported 55 through the final cleansing chamber. The steam distributing spider 5 and the adjacent rotor 6 are drivingly connected by means of parallel pins 11. The rotor 6 of the final cleansing chamber is likewise freely 60 endwise removable from the steam distributing spider 5, and the spider 5 is also endwise removable from the steam distributing header 3.

The final discharge rotor 8 is rotatably 65 mounted upon a stationary pivot 29 and is

movable in an anti-clockwise direction as viewed in Fig. 1. The final can discharge conduit to which the cleansed cans are delivered by the rotor 8, is provided with guides 21 which cooperate with the upper and lower walls of the final discharge passage to deliver the washed cans into the discharge chute 22. The chute 22 is attached to the casing 2 and 70 may be positioned to deliver the cans directly to the filling machines. The cover 7 is attached to the casing 2 by hinges 25 and may be locked in closed position by a releasable clamp 26. The cover 7 incloses both of the cleansing chambers and the conduits communicating therewith, and permits free access to the entire interior of the washer without interfering with the can inlet and discharge chutes 12, 22. The interior of the casing 2 is also provided with suitable passages for conducting water to the drain 23.

The driving mechanism for imparting motion to the movable elements of the washer, consists of a pulley 13, a friction clutch 39, a shaft 38 supporting the pulley 13 and the clutch 39, gearing 37 connecting the shaft 38 with a vertical shaft 36 upon which the feed drum 14 is mounted, bevel gears 35, 34 drivingly connecting the vertical shaft 36 with a counter shaft 33, a pinion 32 attached to an end of the counter shaft 33 and meshing with a gear 4 secured to the hot water distributing spider 5, a similar gear 4 secured to the steam distributing spider 5, and a gear 46 secured to the final discharge rotor 8 and meshing with the gear 4 of the steam distributing spider. The drive shaft 38 is mounted in bearings in the bracket 10 which is angularly adjustably supported upon a stationary adjusting plate 16. The plate 16 is provided with a plurality of spaced holes 49 formed to receive locking bolts 42 in order to positively position the driving mechanism in a desired position of adjustment. The driving coaction between the elements of the friction clutch 39 may be varied by adjustment of the compression of the spring 40, with the aid of an adjusting nut 41 coacting with screw threads on the shaft 38. It will be noted that with this arrangement of elements, motion is transmitted from the drive shaft 38 through the supply drum 14 to the initial washing rotor, from the initial washing rotor to the final cleansing rotor, and from the final cleansing rotor to the discharge rotor 8.

During normal operation of the washer, power is applied through the pulley 13 to impart continuous rotary motion to the horizontal shaft 38 through the friction clutch 39. The rotary motion of the shaft 38 is transmitted through the gear 37 to the can feed drum 14, and through the vertical shaft 36 and gears 35, 34 to the counter shaft 33 and pinion 32. The rotating pinion 32 pro-

duces rotation of the spiders 5, the transporting rotor 6, and of the final discharge rotor 8, in the directions heretofore referred to. As the successive cans 9 gravitate toward the projections 43 on the casing 2, they are pushed endwise by the upper inclined surfaces of these projections, toward the revolving feed drum 14, the helical projection of which engages the adjacent ends of the successive cans. The revolving projection 15 cooperates with the gravity feeding to produce positive mechanical feeding, and gently deposits the successive cans 9 in the notches between the successive can hooks 15 of the initial rotor 6 in properly spaced relation. As the cans 9 are transported through the initial washing chamber with their open ends exposed to the nozzles 18, hot water is delivered into the cans. As each can 9 advances to the space between the two cleansing chambers, its interior besides being subjected to hot water washing, is gradually and additionally subjected to the cleansing action of steam. The hot water jets are eventually removed from the moving cans 9 as they advance into the final cleansing chamber wherein the can interiors are finally cleansed by the action of steam jets delivered from the nozzles 19. The cans 9 are finally delivered by the rotating discharge rotor 8 along the discharge guide 20 in an obvious manner.

The can feed mechanism insures proper delivery of the cans 9 to the machine without damaging the relatively frail receptacles. If a can 9 should become jammed in the positive feed afforded by the drum 14, or between any other moving elements of the machine, the clutch 39 will slip and thus avoid damage. The large cover 7 permits free access to all parts of the interior of the washer, and the various elements are conveniently adjustable and removable to produce most efficient and sanitary conditions of operation. The improved driving mechanism reduces the power consumption to a minimum, and the friction clutch 39 serves as a safety device for positively preventing breakage of parts in case an abnormal object enters the machine. The can inlet and discharge chutes 12, 22 cooperating with the angularly adjustable drive mechanism, facilitate convenient location of the washer, and the vertical feed mechanism is obviously applicable otherwise than in a can washer. This vertical can feed mechanism is extremely simple, compact, positive, and automatic in operation and has been found to produce excellent results in commercial operation.

It should be understood that it is not desired to limit the invention to the exact details of construction and operation herein shown and described, for various modifications within the scope of the claims may occur to persons skilled in the art.

It is claimed and desired to secure by Letters Patent:—

1. In combination, means forming a chamber and a chute for delivering a succession of cylindrical cans with their axes horizontal downwardly toward said chamber, a feed drum having a helical projection extending into one side of said chute, said drum being directly engageable with the open end edges and said projection being rollably engageable with the lower curved side portions of the successive cans passing through said chute to retard the travel of upper cans and to deliver the successive lower cans in definitely spaced relation into said chamber, and means associated with the opposite side of said chute for urging the successive cans into operative engagement with said projection. 70 75

2. In combination, means forming a chamber and a chute for delivering a succession of cylindrical cans with their axes horizontal downwardly toward said chamber, a movable element rotatable about a substantially vertical axis and having a helical projection with which the successive cans passing through said chute are rollably engageable so as to retard the travel of upper cans and to deliver the successive lower cans singly and in definitely spaced relation into said chamber, and means associated with said chute above said projection for urging the successive cans toward the axis of rotation of and into operative engagement with said projection. 80 85 90 95

3. In combination, means forming a chamber and a chute for delivering a succession of cylindrical cans with their axes horizontal downwardly toward said chamber, a feed drum having a helical projection extending into said chute, said drum being engageable with the ends and said projection being engageable with the lower side portions of the successive cans passing through said chute to retard the travel of upper cans and to deliver the successive lower cans in definitely spaced relation into said chamber, and means associated with said chute above said drum for urging the successive cans toward the axis of rotation of and into operative engagement with said drum and said projection. 100 105 110 115

4. In combination, means forming a chamber and a chute for delivering a succession of cylindrical cans with their axes horizontal downwardly toward said chamber, a series of can hooks revolvable about an axis within said chamber, a feed drum having a helical projection extending into one side of said chute, said drum being directly engageable with the open end edges and said projection being rollably engageable with the lower curved side portions of the successive cans passing through said chute to retard the travel of upper cans and to deliver the successive lower cans in definitely spaced relation between said hooks in succession, and means associated with the opposite side of 120 125 130

said chute for urging the successive cans into operative engagement with said projection.

5. In combination, means forming a chamber and a chute for delivering a succession of cylindrical cans with their axes horizontal downwardly toward said chamber, a series of can hooks revolvable about an axis within said chamber, an element rotatable about a substantially vertical axis and having a helical projection with which the successive cans passing through said chute are rollably engageable so as to retard the travel of upper cans and to deliver the successive lower cans singly and in definitely spaced relation between said hooks in succession, and means associated with said chute above said projection for urging the successive cans toward the axis of rotation of and into operative engagement with said projection.

20 6. In combination, means forming a chamber and a chute for delivering a succession of cylindrical cans with their axes horizontal downwardly toward said chamber, a series of can hooks revolvable about an axis within 25 said chamber, a feed drum having a helical projection extending into said chute, said drum being engageable with the ends and said projection being engageable with the lower side portions of the successive cans 30 passing through said chute to retard the travel of upper cans and to deliver the successive lower cans in definitely spaced relation between said hooks in succession, and means associated with said chute above said 35 drum for urging the successive cans toward the axis of rotation of and into operative engagement with said drum and said projection.

7. A device for supporting and releasing 40 successive elements, comprising, a single revolvable upright feed screw adapted to support a stack of elements on its thread at one side of the stack and to successively remove the elements from the bottom of the stack and 45 then release the same, and stationary means at the opposite side of the stack for urging the successive elements onto the thread of said screw.

8. A device for supporting and releasing 50 successive elements, comprising, a revolvable upright feed screw adapted to support a stack of cylindrical elements having parallel axes on its thread at one side only of the stack and to successively remove the lowermost elements from the stack and then release the 55 same at equal intervals, and means at the opposite side of the stack for urging the successive elements longitudinally of their axes onto the thread of said screw.

60 In testimony whereof, the signature of the inventor is affixed hereto.

OSWALD H. HANSEN.
